(57) **CLAIM**

The ornamental design for a wheeled tote with handle, as shown and described.

DESCRIPTION

FIG. 1 is a top perspective view of a wheeled tote with handle;

FIG. 2 is a bottom perspective view of the wheeled tote with handle shown in FIG. 1;

FIG. 3 is a top plan view thereof;

FIG. 4 is a bottom plan view thereof;

FIG. 5 is a right side elevational view thereof;

FIG. 6 is a front elevational view thereof;

FIG. 7 is a rear elevational view thereof; and,

FIG. 8 is another top perspective view thereof, shown with the handle raised.

A left side elevational view is not shown because it is a mirror image of the right side elevational view shown in FIG. 5.

The broken lines in the drawings depict portions of a wheeled tote with handle and form no part of the claimed design.
